UNITED STATES PATENT OFFICE.

CLEMENT CLEVELAND, OF NEW YORK, N. Y.

PENCIL SHARPENER.

Application filed May 19, 1922. Serial No. 562,183.

To all whom it may concern:

Be it known that I, CLEMENT CLEVELAND, a citizen of the United States, residing in New York, in the county of New York and 5 State of New York, have invented certain new and useful Improvements in Pencil Sharpeners, of which the following is a specification.

My present invention relates to that class 10 of pencil sharpeners which usually have a substantially conical form, and are made of small dimensions convenient for carrying in the pocket, and are arranged for first reducing the "wood" and next, by a separate 15 operation, for sharpening the point of the lead, thus effecting the complete sharpening operation by a two-stage process.

The present invention is in the nature 20 of an improvement upon the pencil sharpener described and claimed in the prior Letters Patent, No. 1,327,459, granted to me January 6, 1920, and which may be referred to for a more extended description of the 25 manner in which the cutting edge is arranged for performing the two sharpening operations.

Also, some features herein illustrated are shown in another Patent, No. 1,417,034, dated May 23, 1922.

30 In the accompanying drawing forming a part of this specification, Fig. 1 is a side view of a pencil sharpener embodying my present improvements in a preferred form thereof.

35 Fig. 2 is an end view of a completely assembled sharpener as seen from the right hand in Fig. 1.

Fig. 3 is a plan or top view showing the sharpener as seen from above in Figs. 1 40 and 2.

Figs. 4 and 5 are, respectively, a side view and an end view of the side portion C¹ of the sharpener shown in the preceding views; and Fig. 6 illustrates approximately a form 45 of plate, suitable for being shaped up by proper die methods into the completed form illustrated in the preceding views.

Figs. 7, 8 and 9 are, respectively, a side view (as seen from the left hand in Fig. 2) 50 of the side portion C² of the sharpener; an end view of said portion as seen from the right hand in Fig. 7; and, a plate of an outline suitable for being formed into the completed side portions shown in the preceding views.

Fig. 10 illustrates, in a separate view, an

improved arrangement and device for guiding the wood portion of the pencil when inserting the same into the sharpener for reducing the conical wood portion thereof, and 60 for convenience of illustration this view shows a longitudinal vertical section of the sharpener, and, in dotted lines, the position of a pencil introduced thereto.

Fig. 11 shows the said pencil-guiding device drawn in alinement with Fig. 10, and as seen from the right hand in Fig. 1, and also as seen in Fig. 2.

Similar characters designate like parts in all of the views.

A leading feature of the present improvements will be understood by a comparison of the several figures of the present drawing, and especially by comparison of the same with the illustrations in my said 75 prior patents, to which reference may be had.

In the present instance, the conical portion of the sharpener, instead of being made of a single piece, is formed of two side portions, herein designated as C¹ and C², each 80 of these portions being provided with an extended flange or plate as 2°, 3°, respectively, and being adapted to be affixed each to the other by a simple die process and a brazing or spot welding action accomplished in 85 connection therewith.

The aforesaid method of construction renders available another improvement which is a particular feature of the sharpener herein illustrated, which consists in making the 90 guiding side portion C¹ relatively thicker, or relatively more rigid, or both, than the opposite and coacting portion C², the latter being the knife-edge member of the pair of side portions or plates. Thus, in the operation 95 of the sharpener the flexing of the conical portion whereby the operation of the knife may be automatically self-limited under some of the conditions (as explained and illustrated in my aforesaid Letters 100 Patent), may now be accomplished through the flexing of only one of the side portions of the cone, this side portion being the one having the knife-edge formed at one of the longitudinal edges thereof.

In Figs. 6 and 9, dotted outlines are shown at 3^d and 3^f; respectively, corresponding to the lines similarly designated in Fig. 6 of said prior Patent No. 1,417,034, issued May 23, 1922. These lines represent how incisions may be made in the side plates C¹ and C², whereby to form therein pencil-

guiding springs in accordance with the construction specially illustrated in Figs. 1 to 4 inclusive of said patent, and these pencil guiding devices are adapted to be used in connection with the present improvements, and as regards the principal features hereof are considered to be, broadly, an equivalent for the specific improvement in pencil-guiding means herein specially shown in Figs. 10 and 11, and illustrated in the assembled sharpener as shown in Figs. 1 and 2.

Since the conical portion comprising the two sides C^1 and C^2 is herein shown provided, when assembled, with the plate-form extension E , having an opening near one end thereof which constitutes a holding means whereby the operator may grasp the sharpener and whereby the sharpener may be suspended on a watch chain or key chain, and since this extended plate portion furnishes means for attaching and properly supporting an improved pencil-guiding device, it is therefore deemed preferable to use, in the present instance, a pencil-guiding spring, S , and a preferred form of this is shown in the drawings. This guiding device, see Fig. 11, may consist of a narrow ribbon of steel, or other suitable metal, formed with the two pencil bearings S^1 and S^2 , and with a shank portion S^3 of U-shape which may be inserted through incisions cut at 4° and 5° (Figs. 6 and 9), so that the said shank portion will overlap and may be properly affixed to the narrower end portion 2° of said side plate E , as will be more clearly understood by a comparison of Figs. 1, 2 and 10. Said spring member S having been preliminarily prepared, and the two side portions C^1 and C^2 of the sharpener having been affixed together, (preferably by surface adhesion or welding already referred to), said spring device may then be slipped into place and affixed by riveting in an obvious manner (not shown), or, preferably, by a soldering or brazing operation, or by a directly applied spot-welding process, which, in the present state of that art, is readily employed and will be understood by those familiar therewith without a further description.

In the accompanying drawing the socket D for the end of the lead of the pencil to be sharpened, is illustrated in accordance with the construction set forth in said patent, No. 1,327,459, but it will be understood that in place thereof this socket and provision therefor may be in accordance with the special construction thereof described, illustrated and claimed in said Letters Patent No. 1,417,034 issued May 23, 1922, in which instance the members C^1 and C^2 herein shown in Figs. 4 and 7, will be preliminarily shaped in accordance with the construction which is fully illustrated in said patent of May 23, 1922.

For convenience of description, the two

coacting cone-members C^1 , C^2 have been herein designated as being, respectively, "non-resilient" and "resilient," since these members, when made and assembled in the preferred way herein explained, would normally have those respective modes of action relative to each other while the sharpener in being used is subjected only to a sufficient force, or pressure, for doing the work for which the sharpener may have been properly designed, in any particular instance; but, of course, it will be understood that any part of the device may be flexed, or bent, by subjecting it to a wrong treatment, or to a force relatively abnormal therefor.

Having thus described my invention, I claim:

1. A pencil sharpener, comprising two semiconical members each having a flange portion along one longitudinal edge thereof, said flanged portions being joined together to form a tubular cone and with the free edges of said semiconical members spaced apart and spring tensioned pencil encircling-guiding means within said cone.

2. A pencil sharpener, comprising a resilient semiconical side member and a non-resilient semiconical side member joined together to form a split tubular expansible cone for receiving the lead pencil therein, the free edge of said non-resilient member being a plane edge and the free edge of said resilient member being a knife edge, and means for positioning the plane edge and knife edge for coaction therebetween for cutting by the knife edge.

3. A pencil sharpener, comprising a resilient semiconical side member and a non-resilient semiconical side member joined together to form a split tubular expansible cone for receiving the lead pencil therein, the free edge of said non-resilient member being a plane edge and the free edge of said resilient member being a knife edge, means for positioning the plane edge and knife edge for coaction therebetween for cutting by the knife edge, and spring-tension pencil-encircling-guiding means within said cone.

4. A pencil sharpener for two-stage operation, comprising semiconical members joined together to form a split tubular cone, one of said members having a knife-edge located longitudinally on one side thereof, said knife-edge being arranged near the smaller end of the cone for sharpening the wood of a pencil, a lead-supporting socket formed of the other of said semiconical members and located within the larger end of said cone and in position for coacting with said knife-edge, and spring-tensioned pencil-encircling-guiding means within said cone.

5. A pencil sharpener for two-stage operation, comprising a resilient semiconical side member and a non-resilient semiconical

side member joined together to form a split tubular expansible cone for receiving the lead pencil therein, the free edge of said non-resilient member being a plane edge and the free edge of said resilient member being a knife edge, means for positioning the plane edge and knife edge for coaction therebetween for cutting by the knife edge, a lead-supporting socket formed of said non-re-

silient member and located within the larger end of said cone and in position for coacting with said knife edge, and spring tension pencil-encircling-guiding means within said cone arranged to maintain the pencil in axial alinement therewith during the wood-removing first-stage operation.

CLEMENT CLEVELAND.
